United States Patent Office.

WILLIAM WALLACE, OF ANSONIA, CONNECTICUT.

Letters Patent No. 79,036, dated June 16, 1868.

IMPROVED MACHINE FOR FORMING LAMP-TUBES.

The Schedule referred to in these Letters Patent and making part of the same.

TO ALL WHOM IT MAY CONCERN:

Be it known, that I, WILLIAM WALLACE, of Ansonia, in the county of New Haven, and State of Connecticut, have invented a new Improvement in Forming Lamp-Tubes; and I do hereby declare the following, when taken in connection with the accompanying drawings, and the letters of reference marked thereon, to be a full, clear, and exact description of the same, and which said drawings constitute part of this specification, and represent, in—

Figure 1, a perspective view,

Figure 2 an instrument for forcing the bars, and in

Figure 3 a central section illustrating the operation.

This invention relates to an improvement for forming lamp-tubes or similar articles other than of a cylindrical form, designed specially for forming flat tubes for kerosene-lamps.

The common manner of making these tubes and articles of similar form is to draw out a cylinder to the proper size, and then flat the tube by outward pressure, or hammering upon a bar of the required form. This, in metal of which the tubes are necessarily made, almost invariably forms wrinkles or irregularities in the surface of the tube.

The object of my invention is to avoid the difficulties experienced in forming tubes by the old process, and facilitate the process, and produce a better article; and my invention consists in the arrangement of a pair of bars, the outer edges of which are parallel to each other, or nearly so, and the bars arranged each independent of the other, and so as to be forced from each other, maintaining the same parallel position, and arranged so that both are easily inserted within the cylindrical tube; then, by the forcing apart of the said bars, the tube is spread and stretched into proper form in the most perfect manner.

In order to the clear understanding of my invention, I will fully describe the same as illustrated in the accompanying drawings.

A is one bar, b the other, their two outer edges parallel, or nearly so, to each other. Each of the said bars is attached firmly to the slides A and B, respectively, which said slides arranged in a suitable guide, C, so as to permit the movement of the bars, the one from the other, and yet hold them in their upright position, so that in their movement they retain their parallel position. A convenient manner of spreading the two bars is, as represented in the drawing, to form their two edges inclined outward, so as to receive a wedge, D, the said wedge corresponding to the incline of the two bars, and so that when driven between the bars it will force them apart, as denoted in red, fig. 3.

The thickness of the bars must correspond to the thickness of the tube, and the outer edge of the bar must also conform to the shape desired for the edge of the tube.

The tubes to be formed by this apparatus are first produced in cylindrical form, of the required length, and in the usual manner; then, the two bars closed together, the cylindrical tube is placed over the said two bars, and the wedge D inserted, and driven down to force the bars from each other, which operation spreads and flattens the tube into the form desired, corresponding to the form of the bars a and b when spread; then the wedge is forced out in any convenient manner, the finished tube removed, another placed thereon, and in like manner formed, and so continued.

Various devices may be employed for forcing apart the two bars, but the wedge I have described is a simple and convenient manner. While I do not confine myself to the use of the wedge for this, I yet prefer it for its simplicity.

If, as in some burners, it is desired to make an enlargement upon the edge of the tube, as for the purpose of fixing the tube in its proper position in the burner, a corresponding projection should be formed on the edge of the bars, which will force the metal outward, and form the required projection.

Having thus fully described my invention, what I claim as new and useful, and desire to secure by Letters Patent, is—

The arrangement of the two bars a and b, their outer edges parallel to each other, or nearly so, so as to receive the cylindrical tube, and combined with a device to force the said bars, so as to flatten and form the tube substantially in the manner herein set forth.

WILLIAM WALLACE.
